UNITED STATES PATENT OFFICE.

RICHARD B. STURGEON, OF BURLINGTON, IOWA.

PUZZLE TOY.

Application filed May 3, 1926. Serial No. 106,440.

The invention relates to a toy comprising two blocks pivoted together, a cord passed through passages of said blocks and capable of sliding in either direction and a pair of abutting cord inserts in the inner sides of said blocks which give the appearance that the cord has been severed by passage of a knife blade between the blocks, said blocks being swingable apart to disclose said insert. Regardless of the fact that a person unfamiliar with the device receives the impression that the cord has been cut, the user may swing the blocks back together so that the observer can again pull the cord in one direction or the other and cannot by observing the inserts, determine that they are not actually parts of this cord.

A device of the general character above set forth is old and well known, but the construction is such that if the blocks are rotated one or more revolutions with respect to each other, they will pinch and injure the portion of the cord passing from one block to another, even if they do not entirely cut said cord in two. It is the object in the present invention, however, to provide a distinct improvement over the old construction, whereby instead of being injured by excessive rotation of one block or the other, the cord will merely wrap around the pivot which connects the two blocks.

With the foregoing in view, the invention resides in the novel subject matter herein-after described and claimed the description being supplemented by the accompanying drawing.

Figure 1 is a longitudinal sectional view showing the cord passing properly from one block to the other.

Figure 2 is a similar view partly in elevation but illustrating the manner in which rotation of one of the blocks with respect to the other, will merely wrap the cord around the pivot, instead of injuring said cord.

In the drawings above briefly described, the numeral 3 designates two blocks which are preferably of rectangular form, said blocks having contacting inner surfaces and being connected with each other near one end by the pivot 4 at right angles to said surfaces. The blocks 3 are formed in their inner sides with registering recesses 5 which entirely surround and enclose the central

portion of the pivot 4. Leading longitudinally of the blocks 3, from the recesses 5, 55 are two passages 6, whose outer ends are plugged as at 7, and two lateral passages 8 extend from said passages 6 to the outer sides of said blocks. In line with these passages 8, two cord inserts 9 are provided 60 with their inner ends exposed at the contacting surfaces of the blocks 3, and a cord 10 is passed through said passages 8, through the longitudinal passages 6, and through the recesses 5. Between the inserts 9 and the pivot 4 the inner sides of the blocks 15 are jointly recessed to provide an opening 11 for the insertion of a knife-blade or the like.

In using the device, it is held before an observer with the blocks 3 closed with respect to each other and he is shown that the cord can be pulled in either direction. A knife blade or the like is then inserted in the opening 11 and pulled outwardly as if 75 severing this cord. When the blocks 3 are now swung apart, about the pivot 4, the observer sees the inserts 9 and obtains the impression that the cord 10 has actually been severed. The blocks then are again closed and he is shown that the cord 10 may still be pulled in one direction or the other.

It often happens that children or others in handling or "playing" with the device, will rotate the blocks 3 one or more revolutions with respect to each other. If this is done, the central portion of the cord 10 will merely wrap about the central portion of the pivot 4, instead of being injured by contact with the edges of the blocks, as in the old structure to which I have previously referred. A good showing of this old structure is given in U. S. Patent 47552 of May 2, 1865, in which it will be seen that the transverse cord passage through which the cord passes from one block to the other, is off-center with regard to the pivot and does not entirely surround such pivot, so that pinching and injuring the cord must necessarily take place if the blocks are rotated 90 beyond a predetermined extent with respect to each other.

I claim:

In a toy, two blocks having contacting faces, a pivot passing through said blocks, the latter having registering recesses en-

tirely surrounding and enclosing the central portion of said pivot, having longitudinal passages leading from said recesses, and having lateral passages from said longitudinal passages to the outer sides of the blocks, and a cord passing through said passages and through said registering recesses, the

latter being of a size to allow winding of the cord around said central portion of the pivot if the two blocks are rotated in a manner to cause such winding. 10

In testimony whereof I have hereunto affixed my signature.

RICHARD B. STURGEON.
